UNITED STATES PATENT OFFICE.

HENRY DE BRY, OF OGDEN, UTAH.

SHOESTRING-FASTENER.

1,085,550.

Specification of Letters Patent.

Patented Jan. 27, 1914.

Application filed December 14, 1912. Serial No. 736,872.

To all whom it may concern:

Be it known that I, HENRY DE BRY, a citizen of the United States, residing at Ogden, in the county of Weber and State of Utah, ⁵ have invented certain new and useful Improvements in Shoestring-Fasteners, of which the following is a specification, reference being had to the accompanying drawings.

10 This invention relates to certain new and useful improvements in shoe string fasteners, the object of the invention being to provide a device of this character whereby the ends of the shoe string may be quickly and ¹⁵ securely fastened after the shoe has been laced.

Another object of the invention is to provide a device of this character which will possess advantages in points of efficiency and ²⁰ durability, is inexpensive to manufacture and at the same time is simple in construction and operation.

With the above and other objects in view, the invention consists in the novel features of ²⁵ construction and the combination and arrangement of parts hereinafter more fully described, pointed out in the claim and shown in the accompanying drawings, in which—

10 Figure 1 is an elevation of a portion of a shoe upper illustrating the application of my invention. Fig. 2 is a side elevation of one of the fastening members. Fig. 3 is a longitudinal sectional view of the same. Fig. 4 ⁵ is a detail perspective view illustrating the manner of securing a shoe string.

Referring more particularly to the drawings, 1 indicates the elongated body portion of the fastener, one end of which is provided with an opening 2 whereby the same may be readily secured to the shoe by means of the eyelet 3. The other end of the body is curved upwardly and then downwardly as shown at 4 and the extreme end of the body is provided with a hook member 5 adapted to engage within the leather of the shoe to securely fasten this end of the body.

Upwardly projecting ears 6 are formed upon the longitudinal edges of the body and are adapted to be disposed between the spaced ears 7 formed upon the intermediate portion of the lever 8. The ears 6 and 7 are provided with a transverse opening 9 in which is arranged a suitable pivot pin 10 whereby the lever is pivotally mounted upon the body 1. One end of the lever 8 is provided

with an enlarged portion 11 whereby pressure thereon will manipulate the lever, and the other end of the lever is curved downwardly and then outwardly co-incident with the curvature of the end of the body 1.

It will be apparent that the curved and the front end of the body 1 forms a suitable seat as shown at 12 in which the curved end of the lever 8 is adapted to fit, the lower face ⁶⁰ of the curved end of the lever and the seat 12 are provided with serrations 13 so that when the shoe strings are clamped between the same they will not pull out unless the lever 8 is first released. Mounted upon the pivot pin ⁶⁵ 10 and arranged between the ears 6 is a coil spring 14, one end of which bears against the outer end of the lever 8, while the other end of the spring bears against the body portion 1 so as to normally retain the curved ⁷⁰ end of the lever in engagement with the outer end of the body.

In securing my improved fastener to the shoe, they are adapted to be arranged upon the opposed edges of the upper of the shoe ⁷⁵ 80 and it will also be understood that while there is a fastener arranged upon each side of the opening in the upper, only one need be used.

From the above description taken in connection with the accompanying drawings, it will be readily apparent that I have provided a simple and durable shoe string fastener whereby the loose ends of the shoe string, after the shoe has been laced up, may ⁸⁵ be securely fastened and held in a secure position until the lever 8 has been manipulated to release the shoe string. It will also be understood that the device is extremely simple in its construction and can be manufactured at a comparatively low cost.

While I have shown and described the preferred form of my invention, it will be obvious that various changes in the details of construction and in the proportions may be ⁹⁰ resorted to for successfully carrying my invention into practice without sacrificing any of the novel features or departing from the scope of the appended claim.

What I claim is:

105
A device of the character described comprising the combination with an elongated body portion having an eyelet for engagement through material to secure the body portion in position against said material, a curved hook member projecting from one end of the elongated body portion and adapt-

ed for engagement through the material to prevent turning of the body portion, said curved hook having a raised portion with a concaved seat formed therein above the plane 5 of the body portion, said concaved seat having a plurality of serrations formed therein, and parallel upstanding brackets formed at opposite sides of the body portion; of a lever pivotally mounted upon said brackets and 10 having one end depressed to form a bowl-shaped member provided with serrations upon the convex face thercof, and adapted to normally co-act with the serrations in the

concaved seat of the hook to securely hold an object placed therein, and means to retain 15 the lever in its normal position with the bowl-shaped member formed therein engaged in the concaved seat of the curved hook.

In testimony whereof I hereunto affix my 20 signature in the presence of two witnesses.

HENRY DE BRY.
